EDMUND C. MORGAN, OF MORGAN PARK, ILLINOIS.

MINING-MACHINE MOVING AND HOLDING DEVICE.

1,183,102.

Specification of Letters Patent.

Patented May 16, 1916.

Application filed June 27, 1910. Serial No. 569,170.

To all whom it may concern:

Be it known that I, EDMUND C. MORGAN, a citizen of the United States, residing at Morgan Park, in the county of Cook and 5 State of Illinois, have invented certain new and useful Improvements in Mining-Machine Moving and Holding Devices, of which the following is a specification.

This invention relates to moving and 10 holding devices for mining machines and has for its primary object to provide an improved device of this character for shifting the position of the machine so that after it has completed its work in one position, it 15 may be shifted to a new position under its own power.

One of the objects is to provide an improved combination and arrangement of parts in a device of this character.

Another object is to provide jacks or 20 stays of improved construction which can be efficiently employed coöperatively with other parts mounted on the machine.

Other and further objects will appear in 25 the specification and be more specifically pointed out in the appended claims, reference being had to the accompanying drawings exemplifying the invention, and in which—

Figure 1 is a diagrammatic plan view of a 30 mining machine provided with one embodiment of the device forming the subject matter of this specification. Fig. 2 is a diagrammatic elevation of the same showing the device in operative position to advance the machine. Fig. 3 is a detail elevation of 35 the winding drums and connections, with means for driving the same. Fig. 4 is a side elevation of one form of an improved strut or jack. Fig. 5 is a plan view of a rope 40 clamp employed in combination with other parts of the device. Fig. 6 is a diagrammatic plan view of another embodiment of the device.

In Fig. 1 of the drawings, a mining 45 machine 1 having a cutter frame 2 with movable cutters 3 mounted thereon is shown in suitable position to begin a new cut into a bank of coal 4 shown in cross section in 50 several of the figures. Immediately to the

rear of the mining machine 1 is disposed a jack or strut comprising a post or other suitable compression member 5 preferably circular in cross section, said post being provided on each end with caps or sockets 55 6 provided with projecting lugs or ears 7. Pivotedly mounted on each of the ears 7 is a substantially triangular shaped block or shoe 8 which is provided with a suitable gripping face for engaging opposite walls 60 of the coal pocket or gallery. Movable longitudinally of the post 5, is a ring clamp 9 provided with a clamping wrench or handle 10 whereby said clamp may be rigidly secured to the post in any desired position 65 therealong, said post being preferably disposed to extend horizontally across said gallery or room. Pivotedly mounted on the ring clamp 9 is a clevis or draw bar 11 adapted to be pivotally connected to a slotted projection or lug 12 on the rear of the mining machine 1, by a bolt 13 with a handle 14. At suitable points along the post 5 suitable guides or pulley blocks 15 are provided which are adapted to receive ropes or 70 cables 16 and 17, said ropes being connected at each end to the mining machine. For this purpose, one end of each rope is connected by a hook 18 with a link 19, and said links 19 are pivoted on a pin 20 rigidly carried by the base member of the mining machine. Said pin 20 is preferably located at approximately the center of the machine or a little forward of the center. Disposed at either side of the mining machine 1 are posts 75 80 or jacks each of which, as shown in Fig. 2, preferably comprises the post 21 with a rigidly mounted claw-foot 22 and an adjustable claw-foot 23 which may be moved endwise into engagement with the top wall of coal. Adjacent the rear end of the mining machine 1 is mounted a motor 24 which is preferably the motor which drives the mining machine, the drive shaft of said motor being provided with a driving pinion 25 95 meshing with bevel gears 26 and 27 which are keyed to the shaft 28. Journaled upon the shaft 28 are winding drums 29, 30, which are held against rotating freely on the shaft 28 by providing the periphery of 100

one flange of each with ratchet teeth 31 with which engage respectively pawls 32 and 33 pivotally mounted in a standard 34, within which the shaft 28 is journaled. Splined to the shaft 28 on opposite ends thereof are sleeves or collars 35, 36, which are provided respectively with clutching elements 37, 38, adapted to engage suitable clutching surfaces in the drums 29 and 30 to rotate the same whenever desired in opposite directions. For this purpose, shifting levers 39, 40, are employed, which engage the sleeves 35 and 36 respectively. In this embodiment of the invention, the mining machine 1 may be swung about bolt 13, by throwing in the clutches 37 and 38 separately or simultaneously, thereby connecting the motor 24 into driving relation with the drums 29 and 30, so that the ropes or cables 16 and 17 are played out or taken up and cause the mining machine 1 to be moved either to one side or the other. When it is desired to move the mining machine bodily forward into a new position, the cables 16 and 17 may be arranged as shown in dotted lines in Fig. 1 and in full lines in Fig. 2, the hooks 18 of said cables being in this instance in engagement with eyelets 41 connected with the posts 21 by bands 42.

As shown in Figs. 1 and 4, a jack 43 is employed for use in corners and other close quarters and is provided with stiffening flanges 44 and 45 throughout a portion of its length. The upper portion of the jack 43 is deflected laterally and threaded, said threaded portion being inserted in a threaded socket 46 pointed at its outer end 47 and provided with a hand wheel 48 whereby it may be rotated to adjust its length. The lower end of the jack 43 is provided with a point 49 adapted to impinge the floor of the mine and immediately above the floor line is provided a pulley or other suitable guide 50 for a cable 51. In Fig. 5 is shown a cable clamp which may be employed in conjunction with any of the pulleys or guides and comprises a bifurcated arm 52 pivotally mounted on the axle 53 of the pulley. Within the outer end of the fork 52 is pivotally mounted an eccentric cam 54 which may be oscillated by a handle 55 into and out of clamping engagement with the cable 51.

Referring now to Fig. 6 and to the embodiment shown therein, the mining machine is provided with winding drums indicated collectively by the reference numeral 57 and which are of similar construction to those already described in the former embodiment. Adjacent the rear end of the mining machine, pulleys or other suitable guides 58 and 59 are mounted, over which cables 60 and 61 pass directly to the posts or struts 21'. In this embodiment the mining machine may be swung from one side to

the other by manipulating the drums 57 in such manner as to wind and unwind the cables 60 and 61. Thus if the cable 60 is wound upon one of the drums while the cable 61 is being unwound from the other drum, the machine is drawn bodily toward the strut 21' on the side of the cable 60. A forward movement of the mining machine in this embodiment may be secured in the same manner as pointed out in connection with the other embodiment. The drums 29 and 30 are made to be operable separately so that should the mining machine reach the desired position while there is any slack in one of the cables, such slack may be taken up and the device thereby adapted to hold the machine in operating position.

What I claim is—

1. The combination with a mining machine, of two rigidly mounted stays near the sides of said mining machine, winding drum mechanism on said mining machine, ropes connected at their free ends to said fixed stays and at their other ends fixed to said winding drum mechanism, two guides on the rear of said mining machine, one for each of said ropes, and means for controlling said winding drum mechanism to cause the force exerted on said ropes to shift the mining machine either laterally or longitudinally at will. 95

2. The combination with a mining machine, of two rigidly mounted stays, one opposite one side of said mining machine and the other on the other side thereof, rope winding mechanism mounted horizontally on said machine, two ropes each fixed to said winding mechanism and the free end of one rope connected to one of said stays and the free end of the other rope connected to the other stay, rope guides at the rear portion of said mining machine one for each of said ropes respectively, and means for controlling said winding mechanism to shift the position of the mining machine laterally and longitudinally. 110

3. The combination with a mining machine, of two rope winding drums mounted on said mining machine with their axes each substantially vertical, a single motor connected to said winding drums for operating the same in opposite directions simultaneously, two ropes, one connected to each of said drums, two rope guiding pulleys one mounted at one rear corner of said mining machine and the other mounted at the other rear corner of said mining machine, and anchorages in the mine chamber near the said mining machine, one on each side of said mining machine. 115

4. The combination with a mining machine, of two rope drums concentrically mounted on the rear portion of said mining machine, two ropes one connected to one of

said drums and the other connected to the other drum, the free ends of said ropes being adapted to be connected to anchorages, and power mechanism mounted on said mining machine for driving said drums in opposite directions.

5. The combination with a mining machine capable of being moved about over solid ground, of a strut adapted to be rigidly mounted in a mine back of the mining machine between the walls of the mine chamber, pivot mechanism between said strut and said mining machine, self-acting power mechanism, comprising rope gearing for moving said pivot mechanism along said strut to adjust the position of said pivot mechanism, means for fastening said pivot mechanism in adjusted position, and connections comprising said rope gearing for swinging said mining machine over the ground on said pivot mechanism while the latter is held in adjusted position.

6. The combination with a mining machine, of a strut fixed between the walls of the material to be mined, pivot mechanism between said mining machine and said strut and movable along the same, means for holding said pivot mechanism in adjusted position to prevent movement along said strut, and power apparatus comprising rope gearing for swinging said mining machine on its pivot while held in adjusted position and along said strut when loosened and for moving said mining machine longitudinally when said pivot mechanism is released from said strut.

7. The combination with a mining machine movable over the floor of a mine, of a pair of anchorages one on each side of said machine, two rope winding drums mounted concentrically on said mining machine, two ropes one wound on one of said drums in one direction and the other wound on the other drum in the opposite direction, and one rope having its free end connected to one of said anchorages and the other rope having its free end connected to the other of said anchorages, fixed struts adapted to be placed in the mine in stationary position on opposite sides of the machine to serve as guides for said ropes, rope guiding pulleys at the rear portion of said mining machine, a motor geared to said drums to rotate the same in opposite directions, and two clutches one for each of said drums to effect transmission of power to the same independently of each other.

8. The combination with a mining machine, of a strut located in a fixed position back of the mining machine, rope winding mechanism mounted on said mining machine, ropes connected to said winding mechanism at their inner ends and to the sides of said mining machine at their outer ends, a

plurality of rope guides mounted on said strut, and additional rope guides fixed in the mine near the sides of said mining machine.

9. The combination with a mining machine, of two rotating rope winding drums coaxially and vertically mounted on said mining machine, a motor for operating said rope winding drums, means for controlling said drums, two ropes one connected to each of said drums, two rope guides one for each of said ropes, anchorages toward the rear of said mining machine for said rope guides, additional rope guides near the sides of said mining machine and located in fixed positions, and connections at or near the central portion of the sides of said mining machine for the free ends of said ropes.

10. The combination of a mining machine, a horizontal strut adjacent one end thereof, a support slidable along said strut, the machine being pivotally connected to said support, oppositely disposed guides on said strut, vertical struts on opposite sides of the machine, a pair of winding drums adapted to be rotated in opposite directions, and cables for shifting the position of the machine and holding the same in the position to which it is shifted, each of said cables being wound at one end upon a drum and secured at its other end to the machine distant from said drum, the intermediate portion of each cable being passed about the strut at the side of the machine and through one of the guides on the rearward strut.

11. The combination with a mining machine, of winding mechanism mounted on said mining machine, two rope guides adapted to be anchored in the mine backwardly of said mining machine, two additional rope guides adapted to be anchored in the mine opposite the sides of said mining machine, and ropes connected to the body portion of said mining machine and extending around said rope guides to said winding mechanism.

12. The combination with a mining machine, of a strut near one end thereof, pivot mechanism between said strut and said mining machine and slidable along said strut, automatic rope winding mechanism mounted on said mining machine, a rope connected to said winding mechanism, connections for said rope to effect movement of said pivot mechanism along said strut to adjusted position, and means for securing said pivot mechanism to said strut in adjusted position.

13. The combination with a mining machine, of a strut held stationary between the walls of the material to be mined, pivot mechanism between said strut and said mining machine, rope winding mechanism mounted on said mining machine, ropes connected to said winding mechanism, connec-

tions for said ropes to enable said winding mechanism to swing said mining machine on its pivot, additional connections for said ropes to enable said winding mechanism to move said pivot mechanism along said strut to adjusted position, and means for holding said pivot mechanism in adjusted position.

14. The combination with a mining machine of a strut adapted to be held stationary between the walls in the mine, pivot mechanism between said strut and said mining machine and slideable along said strut, rope winding mechanism mounted on said mining machine, a motor for operating said 10 rope winding mechanism, clutch mechanism for controlling said rope winding mechanism, two ropes connected to said rope winding mechanism, two rope guides mounted on said strut, one rope guide for each of 15 said ropes, fixed struts adapted to be located in the mine opposite the sides of the mining machine and serving as guides one for each of said ropes, connections at the sides of said mining machine for the free ends of said 20 ropes, rope guides at the rear end of said mining machine, and means for holding said 25 pivot mechanism in adjusted position, said struts opposite the sides of the machine also serving to hold the free ends of said ropes when the same are connected to the guides at 30 the rear end of said mining machine, when the pivot mechanism is to be adjusted to a new position.

15. The combination with a mining machine capable of being moved about over solid ground, of shifting mechanism therefor comprising two rope drums mounted thereon, two clutches one associated with each of said rope drums, a motor for operating 35 said rope drums, two ropes each having their inner ends fastened respectively to said rope drums and wound thereon, and two rope guides at the rear portion of said mining machine one rope guide for each of 40 said ropes, the free ends of said ropes being adapted to be attached to anchorages in the mine opposite the sides of said mining machine.

16. The combination with a mining machine, of rope winding mechanism mounted 45 on the rear portion of said mining machine, rope guides adapted to be connected to anchorages in the mine backwardly of said mining machine, additional rope guides adapted to be mounted opposite the sides of 50 the forward portion of the mining machine and connections to the body portion of the mining machine at or near the central portion thereof for the free ends of said ropes.

17. The combination with a mining machine, of rope drum winding mechanism mounted thereon, a motor for operating the 55 said rope drum winding mechanism, two ropes having their inner ends respectively connected to said rope drum winding mech-

anism for power actuation thereby, rope guides at the rear end of said mining machine, one for each of said ropes, additional rope guides, one for each of said ropes each adapted to be anchored in the mine backwardly of said mining machine, and fixed struts located opposite the sides of said mining machine serving as attachments for the free ends of said ropes or as guides therefor when said free ends are anchored to the sides 70 of said mining machine.

18. The combination with a mining machine, of winding mechanism mounted thereon, two ropes each having its inner end fastened to said winding mechanism, 80 the free end of each of said ropes being adapted to be connected to an anchorage in the mine on opposite sides of said mining machine, two rope guides at the rear portion of said mining machine one for each of said 85 ropes, and means for controlling said winding mechanism to exert a pull on either rope alone or both of them simultaneously.

19. The combination with a mining machine slideable over solid ground, of winding mechanism mounted thereon, ropes connected at their inner ends to said winding mechanism, the free ends of said ropes being adapted to be attached to anchorages in the mine opposite the sides of said mining machine, guides for intermediate portions of 90 said ropes, and means for controlling said winding mechanism so that force exerted on one rope alone will shift the mining machine laterally and force exerted on both 95 ropes simultaneously will shift the mining machine longitudinally.

20. The combination with a mining machine, of two rope winding drums mounted on said mining machine, a motor geared to 100 said winding drums to operate the same in opposite directions, two ropes having their inner ends connected respectively to said winding drums and having their free ends adapted to be attached to anchorages in the 105 mine, and means for controlling said winding drums to shift the position of said mining machine.

21. The combination with a mining machine, of two rope winding drums concentrically mounted on said mining machine, two ropes having their inner ends connected 110 respectively to said winding drums, the free ends thereof being adapted to be connected to anchorages, a motor connected to said drums to drive the same in opposite directions, and means for controlling said drums independently of each other.

22. The combination with a mining machine capable of sliding freely over the floor 115 of a mine chamber, of two rigidly mounted stays near the sides of said mining machine, winding drum mechanism on said mining machine, ropes connected at their free ends 120 to said fixed stays and being fixed at their 125 130

other ends to said winding drum mechanism, two guides on the rear of said mining machine, one for each of said ropes, and means for controlling said winding drum mechanism to cause the force exerted thereby on said ropes to shift the mining machine in various directions at will.

In testimony whereof I have signed my

name to this specification, in the presence of two subscribing witnesses, on this 21st day of June, A. D. 1910.
